UNITED STATES PATENT OFFICE.

STEPHEN BALKWILL, OF CLEVELAND, OHIO.

RAILROAD-CROSSING.

1,367,004.

Specification of Letters Patent.

Patented Feb. 1, 1921.

Application filed December 21, 1917. Serial No. 208,236.

To all whom it may concern:

Be it known that I, STEPHEN BALKWILL, a citizen of the United States, residing at Cleveland, in the county of Cuyahoga and State of Ohio, have invented a certain new and useful Improvement in Railroad-Crossings, of which the following is a full, clear, and exact description.

This invention relates to railroad crossings of the type which employ castings preferably manganese castings, which may be assembled to form a crossing, either which is completely formed of castings or formed in part of rolled rails.

15. The object of the invention is to provide such a crossing as specified, which shall be strong and durable and of a construction which will have a certain amount of inherent flexibility at those portions of the crossing 20 where the wheel flange grooves intersect and which are the places in the use of the crossing where breakage occurs, and are subjected to the greatest wear and pounding action by the wheels passing over the crossing. 25 Generally speaking, the invention may be said to comprise the elements and the combinations thereof set forth in the accompanying claims.

Reference should be had to the accompanying drawings, in which Figure 1 is a top plan view of part of a crossing embodying my invention; Fig. 2 is a top plan view of a form of crossing embodying a modified phase of my invention; Fig. 3 is a section 35 upon the line A—A of Fig. 1; Fig. 4 is a section upon the line B—B of Fig. 2; Fig. 5 is a section upon the line C—C of Figs. 1 and 2; Fig. 6 is a section upon the line F—F of Fig. 1; Fig. 7 is a section upon the line D—40 D of Figs. 1 and 2; Fig. 8 is a top plan view of a different form of crossing embodying my invention; and Fig. 9 is a section upon the line G—G of Fig. 8.

In the drawings, as will be seen, I have 45 shown a form of crossing in which the tracks or wheel flange grooves extend at right angles to each other, but it will be obvious that the angles at which the wheel flange grooves intersect may be varied without departing 50 from the scope of this invention.

In describing my invention reference will be made to two types of crossing, one such as shown in Fig. 1, being a crossing which combines cast parts and rolled rail parts. 55 Such a crossing is more particularly intend-

ed for, and known as, a combination steam railroad and street railroad crossing, while in Fig. 8 there is shown a crossing which is completely made up of cast portions.

In Fig. 1 of the drawing only a half of a crossing is shown. It will be understood that there are parallel members 3 and 4 which intersect two other parallel members, one of which is shown at 2. Inasmuch as the member 2 and its parallel member are of the same construction, it will not be necessary to illustrate or describe the member which corresponds with the member 2.

The member 2 is made up of three cast portions indicated at 2^a, 2^b and 2^c.

The member 2 extends between the members 3 and 4 of the crossing and comprises a single casting which in cross section is shown in Fig. 7. The top of the casting is provided with a tread portion 2^d, over which the wheel of a car is adapted to run. There is also a groove 2^e which forms a flange-way in which the flange of a wheel may run. The portion 2^f of the casting, which is adjacent to the flange-way, forms a guard 70 which guides the wheel flange and keeps it in the groove 2^e.

The casting forming the member 2^a is hollowed out for the sake of lightness, and its lower portion is provided with two outwardly extending base flanges 2^g, which are adapted to rest upon the usual ties and to be secured thereto.

The portion 2^a is formed with a recess 2^h and is adapted to receive the projection 2^k 90 to which reference will be made.

The projection 2^k is below the top surface of the crossing portion 2^e and extends a sufficient distance from the said portion, so that there is formed between 2^a and 2^e a 95 transversely extending groove 2^l, which is a wheel flange-way that cooperates with the crossing parts 4 and 5, which are about to be described.

The foregoing construction provides an 100 articulated construction which secures a limited amount of flexibility between the adjacent ends of members 2 and 2^a.

The construction of the portion 2^b is the same as that of the portion 2^c, and the portion 2^b cooperates with the end of the portion 2^a opposite to that with which the portion 2^c cooperates, in the same manner as the portion 2^e.

Cooperating with opposite sides of the 110

portions 2^a and 2^c and at the parts where they abut, are rolled rail members generally indicated at 4 and 5. The rolled rail portion 5 comprises a tread rail 5^a which is 5 the end of a usual track rail. Coöperating with the track rail 5^a is a short rail section 5^b which acts as a brace. There is also a short rail section 5^c which is spaced from the rail 5^a by a filler 5^e. The space between the 10 tread rail 5^a and the short section 5^c forms a car wheel flange groove or way, and the rail section 5^c forms a flange guard or guide. The outer end of the rail section 5^c is cut away to form an enlarged entrance or approach for the car wheel flange.

The construction of the rail portion 4 is similar to that of the portion 5 except that the portion 4 and the portion 3 are between the cast portion 2 and the duplicate cast portion 20 which extends parallel to the portion 2.

The portion 4 comprises a tread rail 4^a, a coöperating strengthening rail member 4^b, and a spaced wheel flange guide rail member 4^d, which last mentioned rail member is 25 spaced from the tread rail 4^a by a filler block 4^e.

The castings 2^b and 2^c are similarly formed so far as the tread portion and wheel flange guard portion are concerned, to that 30 which has just been described; however, these portions 2^b and 2^c are formed with recessed parts indicated at 2^h, which are adapted to receive the ends of the track rails which are secured within the recesses in 35 proper position to coöperate with the crossing.

The rolled rail portion 5^e is cut or chamfered at 5^d in order that the flange of the wheel may have an enlarged opening which 40 guides the wheel flange as it approaches the crossing.

The various members of the casting at each corner are secured together with angle bars or knees indicated at 7 in Fig. 1. 45 There are four such members 7 used at each corner and transversely extending bolts 8 are passed through the angular bars and through the members of the crossing, both the rolled rail portions and the cast portions, 50 thereby holding the various members of the crossing securely together.

The ends of the rolled rail parts which are indicated at 4 and at 5, coöperate with the cast portions 2^a and 2^c, as indicated in 55 Fig. 6. The section showing this construction is taken upon the line F—F of Fig. 1 and shows only the coöperation of the rolled rail portions with the casting 2^c but the portions of the rolled rail parts 4 and 5 coöperate with the casting 2^a in the same manner.

The casting 2^c is provided with recessed portions on the opposite sides thereof, indicated at 2^h, and the rails are formed with projecting portions 4^f and 5^f respectively, thus 60

the end of the rail is supported directly upon the casting.

The recess 2^h extends throughout the length of the castings. The other portions thereof receive the knees or angle bars 7 to 70 which reference has heretofore been made.

From the construction which has just been described it will be seen that due to the manner of engagement between the parts 2^a and 2^c of the crossing and between the parts 75 2^a and 2^b of the crossing, as well as by the construction employed by which the rolled rail portions coöperate with the castings, there is secured an articulated connection which has a limited amount of flexibility 80 due to the fact that the parts may have a slight movement with respect to each other, as a wheel passes over intersection of the flange-ways.

It is at the bottom of the intersection of 85 the grooves in which the wheel flange travels which have thus been made jointed in my construction, that fractures occur in the use of solid cast crossing, and by providing this limited amount of flexibility, the 90 source of breakage is removed, which consequently lengthens the useful life of the crossing.

In Fig. 2 I have shown a slightly different form or construction, by which the portions 9 and 10 of the casting part of the crossing coöperate. The portions 9 and 10 are similar to the parts 2^a and 2^c heretofore described, and differ in that the adjacent ends of the castings are provided with recesses 10^a and 9^a as shown in Fig. 4. Between the ends of the castings and occupied recesses mentioned, is a filler block 11 which extends transversely with respect to the members 10 and 9. This filler block extends beyond the casting portions of the crossing and serves as a filler block to space the tread portions of the rolled rail parts 12 and 13, in a manner similar to that described with respect to the filler block 4^e as 110 shown in Fig. 1. It will of course be obvious that the filler block which coöperates with the rolled rail portions of the crossing, may be made separate and distinct from the filler block which is between the adjacent 115 portions of the castings 9 and 10.

It will be understood that the same construction which has just been described is employed between adjacent ends of the casting 9 and the casting 14 and also with respect to the rolled rail sections coöperating with the castings 9 and 14 at their adjacent ends.

The various portions of the crossing at the corners thereof are secured together and to 125 each other in the same manner as heretofore described.

In Fig. 8 I have shown a form of crossing in which all the members of the crossing are formed of castings. Each corner of the

crossing comprises two approach pieces indicated at 15 and 16, and what may be termed intermediate members 17 and 18. The intermediate members 17 and 18 in turn form 5 parts of adjacent corners of the casting.

Inasmuch as each corner of the casting is formed in the same manner, a description of one corner will suffice for an understanding of the construction of all.

10 The members 16 and 17 are formed in exactly the same manner as that described with reference to the members 2^a and 2^c in Fig. 1, and they are so related to each other as to form a wheel flange-way groove 18, 15 the same as the wheel flange-way 2^b shown in Fig. 1.

The parts 16 and 17 may engage each other by a construction such as shown in Fig. 3, or such as shown in Fig. 4, both of 20 these constructions providing a flexible connection.

The members 15 and 18 engage with opposite sides of the castings 16 and 17, and the manner of engagement is shown in Fig. 9, 25 which is a section taken along the line G—G of Fig. 8.

The manner of engagement between the members 15 and 18 and the members 16 and 17 is quite the same as the manner of engagement between the members 16 and 17. 30 The member 16 at its opposite sides is formed with depressions 16^a and 16^b which are adapted to receive extensions 15^a and 18^a formed on the members 15 and 18 respectively. The flange-way 18^a co-operates 35 with flange-ways 15^b and 18^b formed in the respective castings, and due to the manner of engagement there is a flexible connection which permits of a certain amount of movement or give between the castings as a 40 wheel passes over the tread portions of the respective castings.

At each corner of the casting the treads are held together by means of angle bars or 45 knees as indicated at 20, and the angle bars are held to each other by transversely extending bolts 21 in a manner which will be well understood.

As before stated, the various corners of 50 the crossing are constructed as just described.

Each casting such as 15 and 16 is formed with a recessed portion such as indicated at 16^c which is adapted to receive the end of 55 an approaching rail, the rail being secured to the casting in the recess.

Having described my invention, what I claim is:

1. A railroad crossing having two parallel 60 portions on each of which portions is formed a tread-way and a wheel flange-way, each portion comprising two end members and an intermediate member, which members are in alinement, means forming an articulated connection between said members at

their adjacent ends whereby to provide a degree of flexibility and relative movement between the members.

2. A railroad crossing having two parallel portions on each of which portions is formed a tread-way and a wheel flange-way, each portion comprising two end members and an intermediate member, which members are in alinement, means forming an articulated connection between the members at 70 adjacent ends and form a transverse wheel flange groove, said means of engagement permitting a degree of flexibility and relative movement between the members.

3. A railroad crossing having two parallel portions on each of which portions is formed a tread-way and a wheel flange-way, each portion comprising two end members and an intermediate member, said members being in alinement, means whereby the members engage at adjacent ends with a projection formed on one of the engaging members and a depression which receives the said projection upon the other of the said members thereby permitting a degree of flexibility and relative movement between the members. 85

4. A railroad crossing having two parallel portions on each of which portions is formed a tread-way and a wheel flange-way, 90 each portion comprising two end members and an intermediate member, which members are in alinement, means whereby the end members and intermediate member engage at adjacent ends, said means comprising a projection on one of the engaging members and a recess adapted to receive said projection upon the other of said engaging members, the adjacent ends of engaging members being spaced by the said projections thereby to form a transverse wheel flange groove and also permitting a degree of 95 flexibility and relative movement between the members. 100

5. A railroad crossing having two parallel portions on each of which portions is formed a tread-way and a wheel flange-way, each portion comprising two end members and an intermediate member, which members are in alinement, depressions formed at the opposite ends of the said intermediate member, 110 projections formed upon the said end members which co-operate with the said depressions thereby forming transverse wheel flange grooves and also permitting a degree 115 of flexibility and relative movement between the said members. 120

6. A railroad crossing having two parallel cast portions on each of which cast portions is formed a tread-way and a wheel flange-way, each portion comprising two end members and an intermediate member, which members are in alinement, means whereby the end members and intermediate member engage at adjacent ends and form a trans- 125 130

verse wheel flange groove, two other parallel portions forming a crossing which intersect the first mentioned parallel portions, said parallel portions being formed of rolled 5 rails, said rolled rail portions being formed with a tread rail part and a guard rail part thereby forming a wheel flange-way between them, said rolled rail portions coöperating with the first mentioned parallel parts, and 10 the wheel flange-way formed in the rolled rail parts being in alinement with the transverse wheel flange groove formed in the first mentioned parallel portions.

7. A railroad crossing formed of castings 15 and rolled rail portions, the cast portions forming two parallel track parts, each of which is formed with a tread-way and a wheel flange-way, the track parts each comprising two end members and an intermediate member, which members are in alinement, means whereby the members engage at adjacent ends and form a transverse wheel flange groove, the rolled rail portions extending between and beyond the said parallel cast portions, each rolled rail portion comprising a 25 tread track and a guard track between which is a wheel flange groove, the said wheel flange groove of the rolled rail portion being in alinement with the transverse groove cast portion, and means for holding the various 30 parts of the crossing together.

8. A railroad crossing having a corner portion formed of two alined castings and

two alined rolled rail portions, the rolled rail portions extending at an angle with respect to the cast portions, said cast portions engaging at adjacent ends and forming a transverse wheel flange groove, the rolled rail portions comprising a tread rail portion and a guard rail portion with a wheel 35 flange-way between them, which wheel flange-way is in alinement with the transverse wheel flange-way of the cast members, said rolled rail portions abutting against opposite sides of the cast portions, and 40 means for securing the various members of the corner portion to each other.

9. A railroad crossing having a corner portion formed of castings and rolled rail portions, the said castings being in alinement and formed with a wheel flange groove, a tread portion in the top thereof, said casting members engaging each other with a projection formed on one of said members and a depression to receive the projection 50 formed on the other of the said members, the rolled rail portions abutting against opposite sides of the cast members, the rail portions being formed with projections which extend into depressions formed on opposite 55 sides of the cast members, and means for securing the various members of the corner portion together.

In testimony whereof I hereunto affix my signature.

STEPHEN BALKWILL.
